Primary Examiner — Keith J Wilson*Assistant Examiner* — Assam Y. Fittahy(74) *Attorney, Agent, or Firm* — Muncy, Geissler, Olds & Lowe, P.C.(57) **CLAIM**

The ornamental design for a gasket as shown and described.

DESCRIPTION

FIG. 1 is a perspective view of a gasket showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a sectional view of section line 8-8 in FIG. 6 thereof.

The broken line rectangle illustrated in FIG. 8 shows the location of the sectional view of FIG. 6. The broken line rectangle forms no part of the claimed design.
